MIXING DEVICE FOR GASES.

1,076,684.

Specification of Letters Patent. Patented Oct. 21, 1913.

Original application filed September 20, 1909, Serial No. 518,509. Divided and this application filed January 14, 1910, Serial No. 533,041. Renewed August 23, 1913. Serial No. 786,346.

To all whom it may concern:

Be it known that I, Forrest A. Heath, a citizen of the United States, and a resident of Jersey City, in the State of New Jersey, have invented certain new and useful improvements in Mixing Devices for Gases, of which the following is a specification, reference being had to the accompanying drawings, forming a part hereof.

10 The object of the invention is to provide a mixing device for gas and air, such for instance as issues from the delivery port of a carburetor, for the purpose of more thoroughly commingling said gas and air and of 15 forming thereby a homogeneous mixture.

The main end in view, in the case of the present improvements, is to form the mixing device as a separable or unitary structure which can be introduced between the 20 carburetor and fuel intake of any gas engine and which can be put on and taken off at will, whereby, in the case of attachment to a gas engine, the latter may be run with fuel delivered directly from the carburetor 25 or, by interposing the mixing device, through the medium of the latter. Such an arrangement or relation, besides making the use of the mixing device at all times optional, offers particular advantages in constructing 30 and assembling these gas engine accessories, and in applying them to use under varying conditions and in different structures.

In carrying out the general object of the invention above stated, a mixing device has 35 been devised of the most compact form and so as to constitute a unitary or complete structure. The said device and its coordination with the engine and the carburetor will 40 now be particularly shown and described in connection with the accompanying drawings in which,

In co-pending applications Serial No. 569,525, filed June 29th, 1910, Serial No. 580,177, filed September 2nd, 1910, and Serial No. 590,266, filed November 2nd, 1910, 45 mixing devices are shown which are similar in many respects to the mixing device shown and described in the present application, which is a division of the co-pending application Serial No. 518,509, filed September 20th, 1909.

Figure 1 is a view in side elevation of an engine structure with the invention embed-

ied therein. Fig. 2 is a top plan view of the mixing device removed from the engine and on a much larger scale, and, Fig. 3 is a vertical central section through the same.

The gas engine, denoted by *a*, is shown in a conventional way and, so far as the present invention is concerned, may be of any construction or type whatever. In the present case, for purposes of illustration and explanation, a hydrocarbon engine having two cylinders *b* and *c* is shown in Fig. 1 of the drawings, the intake conduits for the fuel mixture being denoted by *d* and *e* respectively. These conduits lead from a manifold *f* to which, ordinarily, the carburetor, as *g*, would be secured.

In the present case, instead of securing the carburetor directly to the manifold or intake of the engine, a mixing device *h* for the gas and air issuing from the carburetor in a more or less mixed condition is provided or interposed between the carburetor and the manifold, as indicated clearly in Fig. 1. This mixing device, as will be seen from the drawings, consists of a unitary or complete element, having a two-part casing *i*, the two parts of which are secured together by screws *j*, providing a hollow portion *k*, and a mixing element for the gas and air within the hollow portion. From Figs. 2 and 3, the mixing device as a whole will be seen to be relatively flat and the chamber thereof to be relatively shallow.

As shown, the mixing element consists of a screen *l* formed of relatively coarse wire mesh and secured to a fan *m* pivoted in bearings *n* so as to rotate in the plane of the casing. The screen is parallel to the plane of rotation of the fan, and, being secured as it is to the fan, since both the screen and fan are connected to the same member, namely, the pivoted bearing *n*, is rotated whenever the fan is rotated; and the blades upon the latter are so arranged that when gas and air are drawn through the inlet opening of the mixing device below the fan, the fan will be set in rotation, thus causing the screen to cut across the stream of gas and air in a plane substantially normal to the direction in which the gas and air are moving. After the gas and air pass through the screen, they will be delivered through the outlet opening in the top of the mixing

device into the manifold of the engine. In this way, the gas and air will be thoroughly commingled and the mixture, instead of being "streaky" so to speak, will be delivered into the engine cylinder as a perfectly homogeneous gas. The wire mesh, cutting across the stream of gas and air as it does, acts as a stirrer or agitator, and, on account of its relative coarseness, does not impede the movement of the gas and air to any appreciable extent.

It will be apparent from an inspection of the drawings that the fan is a plate with an upstanding edge or flange m' and that the bottom of the plate has fan blades m^2 which are cut therefrom. This fan consists of a one-piece sheet metal circular plate having its marginal edges bent up laterally at substantially right angles thereto for forming the cylindrical rim or upstanding guard flange m' , and the main body portion of the plate has portions thereof cut away to form a series of blades m^2 and intervening openings m^3 . The openings last referred to are of less radial length than the radius of the fan, thus leaving a central web m^4 or portion uniting the inner ends of the blades. The outer ends of the blades are separated from the rims by slits m^5 extending, in the same direction as the rim, from the openings at one edge to a point in proximity of the opposite edge of the blades leaving relatively narrow webs m^6 uniting the outer edges of the blades to the rim. The portions of the outer edges of the blades which are separated from the rim by the slits are deflected laterally upwardly to points in close proximity to the upper edge of the rim. The screen l fits within the upwardly extending flange, and it is apparent that the latter may be secured in place in the fan by any suitable means as by soldering or otherwise, should such be desired.

The mixing device as a whole, constituting a unitary structure and being separable from the engine and carburetor, may be inserted and removed at will. For this purpose, the parts are constructed and arranged so that the carburetor may be fitted directly to the engine and so that the mixing device may be fitted between the engine and the carburetor. In the present case, this is accomplished by providing the carburetor and engine with flanges o and p respectively and by providing the mixing device with corresponding flanges r and s respectively, although it will be obvious that other constructions and arrangements might be adopted for the same purpose. As shown in Fig. 1 where the mixing device is interposed between the carburetor and engine, the flanges p and s are secured together by means of nuts and bolts and the flanges r and o are secured together in the same way. By removing the nuts and bolts from both

pairs of flanges, the mixing device may be removed and the carburetor attached directly to the manifold f , as will be obvious.

The advantages of the foregoing construction and relation of parts have already been referred to and will be obvious without further exposition at this point. It will be clear, too, that on account of the flat and compact form of the mixing device, it may be very readily embodied in existing gas engine constructions. Moreover, it should be noted that the mixing device may be embodied in many different forms as a separable and unitary structure and hence the invention is not limited to the present embodiment shown and described herein.

I claim as my invention:

1. As a new article of manufacture for use in conjunction with a carburetor the combination of a thin, flat, hollow casing having flange portions at opposite ends and a hollow inner portion, and rotatable in the casing, a mixing element comprising a screen and a fan, the latter of which is provided with a cylindrical rim or flange with in which are located the fan blades which extend radially, the screen being parallel with and secured to the fan and fitting inside of the flange.

2. An article of manufacture for use in combination with hydrocarbon engines and comprising in combination a thin, hollow flange casing having therein a revolvably mounted moving element comprising a fan and an agitating member, the fan having a cylindrical rim and fan blades within the rim and the agitating member being a screen which is parallel with the fan, extending across the fan, and in engagement with the rim portion of the latter.

3. A mixing device having a mixing element comprising a central bearing member which permits the mixing element to rotate, a fan member and an agitating member, both of the last mentioned members being secured to the central bearing member, the fan member comprising a cylindrical rim and fan blades therein and the agitating member comprising a screen which is parallel with the fan and which passes across the end of the mixing element and which also fits the rim.

4. In an article of manufacture of the class described, the combination of a two-part casing each part of the casing having integral therewith a web and located between the webs and held in place in the casing by the webs a mixing element comprising a rotatable shaft which supports a connected fan and screen.

5. A mixing device of the class described comprising a screen and fan both mounted on a pivoted bearing, the fan comprising a plate having an upstanding flanged rim and fan blades located within the rim, the screen

having its edges bent downwardly so as to fit within and engage the rim.

6. As a new article of manufacture, the combination of a casing comprising only two main parts and forming a shallow hollow member with inlet and outlet openings, and a mixing element for gas and air pivoted between the main parts so as to rotate within the casing, the said mixing element comprising a fan upon the side next to the inlet opening and a screen parallel with and secured to the fan and located upon the side next to the outlet opening.

7. In a new article of manufacture, a mixing device for use in combination with a hydrocarbon engine having a two-part casing forming a shallow hollow portion with inlet and outlet openings, and a mixing element which moves transversely to the path

of mixture passing through the hollow portion pivotally mounted in said hollow portion on a shaft, each half of the casing provided with webs for supporting the opposite ends of the shaft each of the casing parts provided at one end with flanges for securing the device in place and at the adjacent ends with outwardly extending flange portions through which means outside of the casing pass for securing the parts together on a plane extending transversely to the path of the mixture and located between the webs.

This specification signed and witnessed this 6th day of January, A. D., 1910.
